Patented Nov. 27, 1917.

FIG. 1.

FIG. 2.

A. D. SUTTON
Inventor
By *Geo. Kimmel.*

Attorney

UNITED STATES PATENT OFFICE.

ARTHUR D. SUTTON, OF PITTSBURGH, PENNSYLVANIA.

GAS-BURNER.

1,247,740.

Specification of Letters Patent. Patented Nov. 27, 1917.

Application filed February 17, 1917. Serial No. 149,314.

To all whom it may concern:

Be it known that I, ARTHUR D. SUTTON, a citizen of the United States, and resident of Pittsburgh, in the county of Allegheny 5 and State of Pennsylvania, have invented certain new and useful Improvements in Gas-Burners, of which the following is a specification.

This invention has reference, generally, to 10 heating appliances and the invention relates, more particularly to an improved gas burner.

The dominant object of the invention is 15 to provide a gas burner so constructed as to produce a steady and uniform heating flame and to permit the proper admixture of air therewith, in order that all products of combustion will be consumed.

It is also an object of the invention to 20 provide novel air mixing means, whereby, the heating flame, upon the introduction of air into the burner, will be directly outwardly at substantially right-angles to the burner, thus, affording the greatest possible 25 heating area for the inflowing air.

Among other aims and objects of the invention may be recited, the provision of a burner of the character mentioned with a view to compactness, and in which the number 30 of parts are few, the construction simple, the cost of production small, and efficiency and operation high.

The improvements in the details and arrangements of parts will be apparent from 35 an inspection of the accompanying drawings in connection with the specific description hereinafter contained, and wherein the preferred embodiment of the invention is disclosed for the purpose of imparting a full 40 understanding of the same.

In the drawings:

Figure 1 is a vertical section through my improved burner as applied to an air heating furnace, the furnace being fragmentally 45 shown in section;

Fig. 2 is a horizontal section of the burner; and Fig. 3 is a side elevation of the same.

Similar characters of reference are employed in all of the above described views to indicate corresponding parts.

Referring now more specifically to the several figures of the said drawings, it is to be noted that I have shown by way of illus-

tration, my improved burner as applied to 55 an air heating furnace, the housing of the furnace being fragmentally shown and indicated by the numeral 1 and having arranged adjacent one lower extremity thereof a suitable air inlet 2. An air heating and 60 circulating jacket, comprising a double walled structure 3 is arranged within the furnace housing element 1, preferably, in spaced relation from the inner faces of the side walls of the same. The outermost wall 65 of the jacketing member 3 is extended downwardly and provided with a laterally extending flange 4, while the remaining wall of the same is arranged in spaced apart relation therefrom and has its adjacent extremity offset as a 5, the purpose of which will be subsequently apparent.

With more especial reference to the present improvements, the burner may be stated 70 to comprise an annular body structure composed of a plurality of spaced walls designated by the numeral 6, the outer wall thereof is provided with a plurality of gas outlet and burning openings 6'. The lower extremity of the outer wall of the burner structure 75 is provided with a closure ring 7, the outer marginal edge of the said ring being flanged as at 8 and snugly engaged with the adjacent edge of the outer wall. A similar closure ring 9, of less width than the ring 80 85 7 is arranged adjacent the lower extremity of the inner wall of the burner structure and is flanged as at 10 whereby the same may be snugly engaged with the lower extremity of the said inner wall. To insure positive 90 connection between the flanged portions 8 and 10 and the said closure rings, suitable cement or other form of securing means may be applied at the point of jointure. To close 95 the space between the remaining extremities of the closure rings 7 and 9, a flanged sleeve 11 is provided and as will be noted, has the several flanges thereof so arranged as to overlap the adjacent end of the said closure rings, whereupon a suitable cement or other 100 fastening means is applied to the same, thus, providing an efficient chamber between the several walls of the burner structure and also maintaining the same in spaced apart relation. To close the upper extremity of 105 the double wall burner structure, the upper ends of the several walls thereof are curved inwardly as at 12 while the outer wall is

provided with a slight extension, which extension is crimped to provide means whereby the offset portion 5 of the inner wall of the air heating and circulating jacket 3 may be received thereby, the said offset portion resting upon a shoulder as formed by the curving of the upper extremity of the outer wall of the burner structure. The curved upper extremity of the inner wall of the burner structure is so arranged as to closely engage the adjacent portions of the outer wall of the same and to insure proper jointure of the same, whereby, to prevent the escape of gas or other fuel from the chamber 15 of the said burner, a suitable form of cement or other packing is applied over the same.

With a view toward providing means whereby the introduction of air into the burner structure will be permitted, there is 20 formed within the inner wall of the said structure, a plurality of openings, generally indicated by the numeral 13, which openings may be of any suitable size, such as conditions or preference may dictate. In 25 the present embodiment, these openings are shown of a size slightly greater than the gas outlet and burning openings 6', although, it will be understood that should it be desired, the size of the openings may be 30 reduced to accord with the size of the said gas burning openings and the number of the same increased to permit the proper admixture of air with the combustible gas. By so arranging the various air inlet openings 13 35 within the inner wall of the burner structure, the heating flame passing through the various gas burning openings 6' will be directed outwardly at substantially right-angles to the vertical wall of the said burner, 40 thus producing the greatest possible heating area for the inflowing air, that is, that air passing upwardly between the housing and circulating jacket 3. Further, it is to be also appreciated, that by so admitting 45 the air, all of the products of combustion of the gaseous fuel will be consumed.

A gas inlet opening is formed within the closure ring 7 and has arranged adjacent the same an internally screw threaded nipple 14, which in turn, has engaged therewith, a complementally threaded portion of a gas supply pipe or main 15, the said main 50 extending through a suitable opening formed in one portion of the furnace housing element 1 into engagement with a suitable gas source.

When positioning the burner 6 within the furnace, the lower portion of the same, that is, the outer portion of the closure ring 7 is 55 engaged with the laterally extending flange 4, and as hereinbefore stated, the crimped flange or extension as formed upon the upper extremity of the burner structure is engaged with the offset portion 5 of the inner 60 wall of the air heating and circulating jacket

3. With the burner so positioned in the furnace, gas may be now admitted to the same by way of the main 15 and ignited at the discharge openings 6' by means of a suitable pilot light or the like. By the peculiar arrangement of the gas outlet and burning openings 6', it will be evident, that a steady and uniform heating flame will be produced, which heating flame by the introduction of air into the burner structure, will 70 be forced outwardly at substantially right-angles to the same, thereby, providing a plurality of flame jets. To insure the heating of the air as passing upwardly through the air heating and circulating jacket 3, the various 75 burning openings 6' may be and preferably are formed within the outer wall of the burner structure in staggered relation.

From the foregoing, it will be appreciated by workers in the art, that I have provided 80 an exceedingly simple and efficient gas burner, and one which by reason of its mounting within the furnace housing may be readily removed from the same to facilitate repairing or cleaning of the several 85 parts thereof.

I claim:

1. In a device of the class described the combination with a double wall air heating jacket, the outer wall of said jacket depending below the inner wall thereof, inwardly extending supporting means thereon, and a double wall perforated gas burner supported thereby with its outer wall arranged in spaced parallel relation with the depending outer wall of the jacket. 95
2. In a device of the class described the combination with a double wall air heating jacket, the outer wall of said jacket depending below the inner wall thereof, an inwardly projecting flange on the lower edge of the same, a double wall gas burner supported on this flange with its outer wall arranged in spaced parallel relation with the depending portion of the outer wall of 100 said jacket, and means for detachably connecting the upper edge of the burner with the lower edge of the inner wall of said jacket. 105
3. In a device of the class described the combination with a double wall air heating jacket, the outer wall of said jacket depending below the inner wall thereof, an inwardly projecting flange on the lower edge of the same, a double wall gas burner supported on said flange with its outer wall arranged in spaced parallel relation with the depending outer wall of the jacket, a bead on the said wall of the burner adjacent the upper edge thereof, and the lower edge 115 of the inner wall of said jacket being adapted to snap over said bead and engage its upper side to securely hold the burner in position. 120
4. In a device of the class described the 130

combination with a double wall cylindrical air heating jacket, said jacket having an opening in its inner wall adjacent the bottom thereof, a double wall annular burner having an open top, and an aperture in the bottom thereof, the vertical walls of said burner being perforated, a gas inlet to the

burner, and means for detachably positioning said burner in the jacket so that its outer wall will cover the opening in the inner wall of the jacket.

In testimony whereof, I affix my signature hereto.

ARTHUR D. SUTTON.
